[57] ABSTRACT

The invention comprises a scope rest device for a gun having a scope mounted thereon. The scope rest device has a socket adapted to be attached to the waist of an operator of the gun with the open end of the socket extending upward. The socket is of a size to closely and detachably receive and support the eye piece end of the scope of the gun with the barrel of the gun extending upward. A strap is provided having a loop at one end which extends about the neck of the operator and which has a clip at the other end to detachably engage the barrel of the gun to maintain the gun in at least a rear vertical position while it rests in said socket of said device.

GUN SCOPE REST DEVICE

This invention relates to supply devices more particularly the invention relates to a scope rest.

It is an object of the invention to provide a novel scope rest having a socket which is attachable to the belt about the waist of a person, which socket detachably receives the eye piece end of a scope of a gun for supporting the gun by the scope, with a strap that surrounds the neck of the person and with a clip at the outer end of the strap to detachably engage the barrel of the gun to hold the gun in an upright manner while supported in the socket.

It is another object of the invention to provide a novel scope rest for supporting a gun by the scope which has a socket of a size to receive the end of the scope and which socket is attached to the belt of the wearer to support the scope in the socket and thereby support the gun and scope and which acts to support the scope and gun in an upright manner.

It is a further object of the invention to provide a novel scope rest for a scope attached to the gun for supporting the gun by the scope on the operator.

Further objects and advantages of the invention will be apparent as the description proceeds and when taken in conjunction with the accompanying drawing wherein:

FIG. 1 is a side elevational view of the scope rest invention with the scope rest socket member shown attached to the belt of the operator and with the gun supported by the scope resting in the socket member, and with the barrel of the gun supported in an upright manner by a strap looped about the neck of the operator and detachably connected to the barrel.

FIG. 2 is an enlarged fragmentary side elevational view of the scope rest socket member and the detachable strap.

FIG. 3 is a front elevational view of the scope socket member supporting the eye piece of the scope of the gun.

FIG. 4 is a top plan view of the scope socket member supporting the eye piece of the scope of the gun.

FIG. 5 is a fragmentary top plan view of the clip of the strap attached to the barrel of the gun.

FIG. 6 is a front elevational view of the scope socket member illustrating the modified form of attaching the socket member to the belt by hooks.

FIG. 7 is a side elevational view of the scope socket member illustrating the modified form of attaching the socket member to the belt by hooks.

Briefly stated, the invention comprises a scope rest invention for supporting a gun on a wearer or operator by a socket member which is attached to the belt of the wearer, said socket member being of a size to receive and support the eye piece end of the scope of the gun, and thereby support the gun on the belt of the wearer, a strap surrounds the neck of the operator and the strap has a clamp at one end to detachably engage the barrel of the gun to align the gun in a generally upright parallel relation to the body of the operator, while the gun is supported by the scope in the socket.

Referring more particularly to the drawing, in FIG. 1, the scope rest invention 20 is illustrated as having a scope rest socket and belt attachment member 21 which is attached to the belt 22 of the wearer or operator 23. A gun 24 has a scope 25 mounted thereon, and the eye piece end 25' of the scope is detachably re-

ceived in the socket member 27 of the scope rest member 21. A leather strap 28 of the scope rest invention 20 has a loop at one end 28' which surrounds the neck 31 of the wearer operator 23. A metal clip 32 is mounted to the other end of the strap 28 and the clip or clamp 32 detachably engages the barrel 33 of the gun 24.

The scope rest socket member 21 has a leather panel 34 with a pair of slots 35 and 35' which receive the belt 22 of the operator 23, with the belt 22 being attached about the waist 23' of the wearer or operator as illustrated in FIG. 1. A T-shaped leather panel member 35 forms a socket 27 for the socket member 21 having a center portion 36, with a base leg 37 folded under from the center portion and extending horizontally and perpendicularly toward the panel 34 and with the outer end 37' of the base leg folded downward and parallel to and abutting the panel 34. A rivet 38 holds the outer end 37' flush and in abutting relation to the panel 34.

The T-shaped leather panel member 35 has side leg portions 39 and 40 with their inner portion 39' and 40' folded perpendicularly and upright toward the panel 34 and with their outer ends 39'' and 40'' folded to perpendicular and vertically outward and away from one another and extending parallel to the panel 34 and riveted to the panel 34 by rivets 41 and 42.

The center portion 35 and side portions 39' and 40' form three of the four sides of the socket, with the area 43 forming the fourth side. The center portion 35, side portions 39' and 40' are extended parallel to panel 34 and with one another and extend generally vertically upward when socket member 21 is attached to the belt 22.

The eye piece end 25' of the scope 25 is freely and detachably received in the socket 27 of the socket member 21 formed by the sides 36, 39', 40', and 43, with the horizontal base leg portion or bottom 37 of the socket member 21 supporting the bottom end 25'' of the scope 25.

The strap 28 has its one end 28' looped about the neck 31 of the wearer with a buckle 44 attached to the outermost arch 28'' of the strap. The strap 28 has a plurality of holes 45 at spaced intervals along the intermediate portions 46, the strap 28 for the rod member 46' of the buckle to project through to adjust the buckle 44 to different positions along the strap to adjust the size of the loop about the neck of the wearer. A lateral loop strap 47 is fixed to the strap 28 at the buckle and loops and freely about the intermediate portions 46 of the strap to keep the buckle in operative alignment.

The other end 30 of the strap 28 has a relatively small loop formed therein by the remote end 30' being reversely folded. A pair of rivets 48 and 49 secure the outermost end 30' of the strap to an adjacent portion 30 of the strap.

The clip 32 is made of spring steel and is rotatably mounted to the strap 28 of the small loop by a pin 50 which passes through a bore in the clip and through a bore in the strap 28 in the small loop portion. The pin 50 has enlarged heads at each end which are larger than the bores to retain the clip and strap together, while the clip 32 may rotate on the pin 50 relative to the strap 28. The legs 51 and 52 of the clip 32 have rounded cylindrical portions 51' and 52' which act to surround the barrel of the gun, with the legs being urged against the barrel to retain the clip 32 on

the barrel. The outermost ends 51" and 52" of the legs are bent outward to facilitate the attachment of the clip to the barrel of the gun.

Operation

The scope rest invention operates as follows:

The scope rest member 21 will be attached to the belt 23 of the operator by inserting the belt 22 through the slots 35 and 35' of the panel 34 and thereafter the belt will be attached on the belt loops on the trousers of the wearer about the waist 23' of the operator.

When the wearer or operator wishes to rest the gun 24 so that his hands will be free, he will insert the eye piece end 25' of the scope 25 of the gun into the socket 27 of the socket rest member 21, and the scope will rest upon the bottom 37 of the socket member 21. The strap 28 is attached to the neck of the wearer as illustrated in FIG. 1. The operator will attach the clip 32 of the strap to the barrel 33 by slipping the clip over the barrel 33 with the resilient legs 51 and 52 grasping the barrel and holding the clip on the barrel, and with the strap thereby holding the gun 24 in a vertical or near vertical position as illustrated in FIG. 1.

The upright vertical walls 36, 39', 40' and 43 of the socket 27 tend to extend vertically and will also act to urge the scope and thereby urge the gun into a vertical upright position.

When the operator wishes to free the gun 24, he will simply grasp the gun 24 by the stock near the clip 32 with one hand and with the other hand pull the clip 32 off the barrel 33. The force of the pulling movement will cause the legs 51 and 52 of the clip to expand and slip off the barrel. He will then lift the gun 24 upward and place the gun in firing position and fire.

As an alternative method of removing the clip 32 from the barrel, the operator may also pivot the gun slightly forward in a counterclockwise direction when viewed from FIG. 1, causing the strap and loop portion to become taunt against the neck of the operator and the pivot action of the gun forward away from the operator will pull the clip off the barrel.

The gun scope rest member 21 may receive the scope of the gun and support the gun by the bottom 25" of the scope resting in the socket 27, without attaching the clip member 32 and scope and gun will simply be suspended in the socket. The upright walls 36, 39', 40', and 43 will tend to urge the gun 24 in a vertical position. The operator may engage the bottom of the butt of the gun with his leg to further help the gun in a vertical position or rear vertical so that the operator will also have his hand free when not using the clip.

The wall members 36, 39', 40', each being parallel to the panel 34 and the panel portion 43, and the panel 34 being generally vertical when attached to the belt of the wearer and the wearer is standing vertical, will tend to urge and maintain the scope and thereby the gun 24 in a vertical or near vertical position when the scope is resting in the socket member, while the clip 32 when attached to the barrel of the gun further acts to keep the gun in a vertical position or substantially vertical position as illustrated in FIG. 1.

The leather socket member 21 being of relatively soft leather will not damage or impair the scope when it rests in the socket member. However, the socket member may be made of other materials such as plastic or rubber, if sufficiently soft, or it may be made of rigid

material, if suitably lined with soft lining material.

Also, as an alternate form of the invention a pair of wire rods 53 and 54 may be provided which have their lower ends fixed to the panel 34, and have hooks 53' and 54' at their upper ends which hook over top edge of the belt 22 of the wearer to attach the panel 34 to the belt in lieu of the slots 35 and 35'.

Thus it will be seen that a novel gun rest invention has been provided which enables the gun to be supported by the scope in a vertical or near vertical position, so that the operator may walk or move about freely without having to hold the gun, and with his hands free without having to set the gun down each time.

Also the gun is supported in the scope rest socket member to a height, as illustrated in FIG. 1, so that the butt of the gun will extend down near the knees of the operator. As a result the scope rest support device supports the gun at a suitable height so that the upper end of the barrel will not stick up above the head of the wearer or operator. It will not stick up as high, as if for example, the operator were carrying the gun in an arm sling, and consequently, the upper end of the barrel of the gun is not as likely to catch branches when the operator is walking through a wooded area with the gun in the scope rest position.

The center of gravity of the gun when the gun scope is resting in the scope socket is such as will tend to pivot the gun counterclockwise when viewed from FIG. 1.

Also, the gun scope rest invention enables quick firing as the operator need only detach the clip and raise the gun into firing position, which can be done easily, rapidly, and conveniently.

It will be obvious that various changes and departures may be made to the invention without departing from the spirit thereof, and accordingly, the invention is not limited to that specifically described in the specification or as illustrated in the drawing, but only as set forth in the appended claims wherein:

What is claimed is:

1. A gun scope rest device in combination with a gun having a barrel with a stock at one end of the barrel and a scope mounted to the barrel intermediate the length of the gun, said scope having an eye piece end directed toward the stock end of the gun, said gun scope rest device comprising a socket member with an open upper end, said socket member having front and rear walls and side walls of a uniform width to form a socket of uniform dimension, a belt for attachment about the waist of a wearer, said socket member having attachment means with elongated openings on each side of the socket lying in the same horizontal plane as the back wall of said socket member for attachment of the socket member in upright fixed relation to the belt, said openings being the sole means of support for said socket, said socket member being of a uniform size only slightly larger than the eye piece end of the scope to closely and detachably socket the eye piece end of the scope into the socket member, whereby said socket member will tend to hold and urge the scope in an upright position, a strap with a loop portion at one end for encircling the neck of the wearer, said strap having a clip at its other end to detachably engage the barrel of the gun and along with the socket retains the gun in an upright position in front of the user.
